UNITED STATES PATENT OFFICE.

ROBERT W. SCOTT, OF PHILADELPHIA, PENNSYLVANIA, ASSIGNOR, BY DIRECT AND MESNE ASSIGNMENTS, TO SCOTT & WILLIAMS, INCORPORATED, OF CAMDEN, NEW JERSEY, A CORPORATION OF NEW JERSEY.

MAKING WIDENED KNITTED WEBS.

1,056,593.

Specification of Letters Patent.

Patented Mar. 18, 1913.

Application filed April 18, 1904. Serial No. 203,708.

To all whom it may concern:

Be it known that I, ROBERT W. SCOTT, a citizen of the United States, residing in Philadelphia, Pennsylvania, have invented 5 certain Improvements in Making Widened Knitted Webs, of which the following is a specification.

My invention consists of a certain method of producing shaped or fashioned knitted 10 web, the web having widening wales introduced without the use of transfer points for conveying stitches from needle to needle, or of a filling up point for conveying an already formed stitch to a vacant needle, the 15 formation of eyelet holes or gaps in the web at the points where the widening wales are begun being also avoided.

The present invention is, in some respects, a modification of that forming the subject 20 of Letters Patent No. 614,349, granted to me November 15, 1898.

In the accompanying drawings, Figure 1, is an exaggerated view of sufficient of a piece of knitted fabric to illustrate my present invention, Figs. 2, 3, 4 and 5, are views 25 illustrating the manner in which each widening wale is introduced, Fig. 6, is a view illustrating another construction of fabric embodying my invention; and Figs. 7, 8 and 9, are diagrams illustrating different 30 dispositions of needles which may be adopted in machines designed for the production of my improved fabric.

In Fig. 1, I have shown fourteen successive courses of a web into which six widening wales have been introduced, three on each side of the central line $\alpha-\alpha$; although the widening may only be on one side, if desired. In the first, second, third and 40 fourth courses of the web, each side of the latter is composed of two standing wales a^1 and a^2 , and four bordering wales b^1 , b^2 , b^3 and b^4 , an additional wale a^3 being introduced in the sixth course, a second additional wale a^4 being introduced in the ninth course, and a 45 third additional wale a^5 being introduced in the twelfth course. The opposite portions of the web in the first, second, third and fourth courses are separated by floating 50 threads a , or, as they may be more properly termed, elongated sinker wale courses, and the length of these sinker wale courses is gradually diminished as the opposite portions of the web are widened by the intro-

duction of the additional wales, until, 55 finally, the two portions of the web join and form a continuous fabric, although this is not essential. The bordering wales may represent the edge portions of two flat webs, or they may be the opposite edge portions 60 of a single web, and, instead of being connected by elongated sinker wale courses, they may, in some cases, have selvage edges. The opposite edges of the narrow web or webs and of the portions in which the 65 widening has been effected, can be united by means of an ordinary looping machine, or by sewing or in any other available manner, the sinker wale courses a being removed, if desired.

So far as described, the present fabric is similar to that of the patent before referred to, the main difference between the two fabrics being in the manner of introducing the widening wales into the fabric.

In the patented fabric, the innermost of the bordering wales was crossed by each widening wale at the point of introduction of the latter into the web, but in the present fabric the initial course of the widening 80 wale engages with a preceding sinker wale course of the fabric, the term "sinker wales" applying to those portions of the fabric where the knitting yarn crosses from one needle wale to another, and the term 85 "needle wales" applying to the rows of intermeshed loops drawn by the needles.

Referring to Fig. 1 of the drawing, it will be observed that the first widening wale a^3 is drawn in course 6 and engages with 90 the sinker wale course 5 between the standing needle wale a^2 and the first of the bordering wales b^1 , the second widening wale a^4 being drawn in course 9 and engaging with the sinker wale course 8 between the needle 95 wales a^3 and b^1 , and the third widening wale a^5 being drawn in course 12 and engaging with the sinker wale course 11 between the needle wales a^4 and b^1 . The effect of this will be either to lengthen the initial course 100 of the widening wale in respect to the courses of the needle wales on each side of the same, or to lengthen the courses adjacent to the initial course of the introduced wale and to the sinker wale course with which it 105 engages. As shown in Fig. 1, the sinker wale course with which the initial course of each widening wale engages, is under

such tension as to be deflected but little, if any, from a straight line, and the initial course of the widening wale is materially elongated. When the courses above and below the initial course of the widening wale are elongated there may be a corresponding contraction of the said initial course of the widening wale, and also a contraction of the needle wale or wales on each side of the same, and in either case the effect may be enhanced by shortening the stitches in a wale or wales on each side of the introduced wale, for instance, in the fabric shown in Fig. 1, such short stitches are formed in courses 5, 8 and 11, while in the fabric shown in Fig. 6, short stitches are formed in wales on each side of the widening wale in courses 5, 6, 10, 11, 15 and 16.

The manner of effecting the intermeshing 20 of the wales will be understood on reference to Figs. 2, 3, 4, and 5. In Fig. 2, A' and A² represent the end needles of a set for the production of the standing wales a' and a², and B', B², B³ and B⁴ represent the needles 25 of the set for forming the bordering wales b', b², b³ and b⁴. The needles, or the stitch-holding portions of the needles of the set for producing the standing wales, and the needles, or stitch-holding portions of the 30 needles, of the set for producing the bordering wales, are movable relatively to each other, both in the directions of the arrow y, Fig. 2, and in the directions of the arrow x, Fig. 2, although said bordering needles, 35 or the stitch-holding portions of the same, may, if desired, be permanently offset in respect to the standing wale needles in the direction of the outwardly pointing arrow x, to an extent which will not interfere with 40 the delivery of the knitting yarn to both sets of needles by the same yarn guide. Preferably, however, the bordering needles, or the stitch-holding portions of the same, have movement in respect to the standing 45 wale needles, or the stitch-holding portions of the same, this being a more convenient arrangement than the reverse construction. During the knitting of the narrow fabric, the needles occupy the relation to each other 50 shown in Fig. 2, but when it is desired to effect a widening of the web, the needles B' to B⁴ are first moved away from the needles A' and A², as shown in Fig. 3, so as to pull up the bordering wales beyond the standing 55 wales, and thereby direct the sinker wale course between the needle wales a² and b' into such position that it can be engaged by an additional standing wale needle A³, brought into action alongside of the needle 60 A². The bordering wale needles B' to B⁴ having moved laterally to the extent of one wale, are then restored to their normal position, or to a position in line with the standing wale needles, the effect of this movement 65 being to restore all of the courses of the

bordering wales into line with the corresponding courses of the standing wales, the last course of bordering wales, however, being displaced laterally in respect to the previous courses to the extent of one wale, as shown in Fig. 4. In the production of course 6, therefore, the needle wale a³, formed upon the needle A³, will engage with the sinker wale course between the wales a² and b', as shown in Figs. 1 and 5. The knitting yarn is fed to each introduced needle on the next movement of the yarn guide after such introduction, at which time said introduced needle is operated to draw a loop of said yarn.

Another method of carrying out my invention when short loops are formed in the wales adjacent to the sinker wale course engaged by the widening wale, is to effect simply a lateral shifting of the bordering wale needles, and the introduction of a widening needle between the same and the last of the standing wale needles by moving said needle from a position outside of the range of the knitting cams to a position 80 within the range of the same, so that in forming the next course the knitting yarn will be laid flat across the face of the introduced needle, and will thus constitute a sinker wale course through which a loop 85 will be drawn by the widening needle in the formation of the next course, the tension upon this sinker wale course due to the short stitches on each side of the same, being relied upon to draw it so tightly between the 90 adjoining wales as to prevent the formation of an eyelet hole of objectionable size between said sinker wale course and that preceding it, or this introduced needle may not be drawn below the edge of the needle carrier, so that no excessive sinker wale course 95 will occur. The number of wales in the band which borders the widened portion of the web, may be varied as desired without departing from my invention.

It will be evident that my improved method of introducing the widening wales so as to close the eyelet hole, may be adopted in the formation of either tubular webs, or flat selvaged edge webs produced by reciprocating knitting, as well as in the formation of a web having divided portions connected by elongated sinker wale courses. The latter method is preferred, however, as it permits of round and round knitting and the use of more than one yarn feed, thus facilitating production and providing for the use of yarns of different color, character or material for successive single courses of the knitted web. The web may be widened by the simultaneous introduction of a plurality of wales, instead of by introducing single widening wales, as described.

The needle plan of a machine upon which a fabric of the character shown in Fig. 1

may be produced, is represented diagrammatically in Fig. 7, A representing a segmental set of standing wale needles, and B two sets of bordering needles which are 5 movable in respect to the standing wale needles, as described, so as to start the knitting with a number of the standing wale needles at each end of the set, (the unshaded needles for instance) out of action, these 10 needles being successively brought into action for widening purposes, as the bordering wale needles are moved, so as to permit such introduction. The yarn in this case is laid round and round and crosses the gap 15 between the needles B B.

The needle plan of a straight machine for producing tubular webs widened in the manner described is shown in Fig. 8, in which A A represents two straight sets of 20 standing wale needles, and B B, two sets of bordering wale needles. The yarn is laid up one side of the machine and down the other, crossing at each end, and its travel may be graduated so as to be co-incident 25 with the active needles, or it may travel throughout the full width of the machine with suitable take-up for the slack yarn at that end of the machine where the widening is being effected, and in this case the 30 sinker wale courses uniting the webs will be of normal and uniform length.

The needle plan of a machine for producing a flat selvaged web widened in accordance with my invention, is shown in Fig. 9, 35 in which A represents the standing wale needles disposed in a single straight bed, and B B, the bordering wale needles, one set operating at one end of the needles A, and the other at the opposite end of the same. 40 The yarn guide in this case travels back and forth along the line of needles, having either a graduated movement or means for taking up the slack yarn at each end of the active set of needles, as desired.

45 When a machine of the type shown in Fig. 7 is employed the knitting yarn, instead of being carried across the gap between the opposite sets of bordering needles B, may be cut off as it leaves one set and laid in again 50 when it reaches the other set, with the result that short ends of yarn will, at each course, project from the outermost of the bordering wales, as shown in Fig. 6. These short ends

may not interfere with the sewing or looping together of the opposite bordering wales, 55 or they can be readily trimmed off if objectionable in that respect.

Having thus described my invention, I claim and desire to secure by Letters Patent,

1. The mode herein described of producing a knitted fabric having a widened portion, said mode consisting in displacing a previously formed normal sinker wale yarn located between needle wales of the knitted fabric and engaging the needle for forming 65 the initial loop of the widening wale with said displaced normal sinker wale yarn.

2. The mode herein described of producing a knitted fabric having a widened portion with bordering wales, said mode consisting in displacing the previously formed normal sinker wale yarn between a standing 70 wale and a bordering wale mounted upon the needles and engaging the needle for forming the initial loop of the widening wale with 75 said displaced normal sinker wale yarn.

3. The mode herein described of producing a knitted fabric having a widened portion, said mode consisting in displacing a 80 previously formed normal sinker wale yarn located between needle wales of a knitted fabric and engaging the needle for forming the initial loop of the widening wale with said displaced normal sinker wale yarn, and 85 drawing the initial loop of the widening wale around said normal sinker wale yarn.

4. The mode herein described of producing a knitted fabric having a widened portion with bordering wales, said mode consisting in displacing a previously formed normal sinker wale yarn between a standing 90 wale and bordering wale mounted upon the needles, and engaging the needle for forming the initial loop of the widening wale 95 with said displaced normal sinker wale yarn and drawing the initial loop of the widening wale around said normal sinker wale yarn.

In testimony whereof, I have signed my 100 name to this specification, in the presence of two subscribing witnesses.

ROBERT W. SCOTT.
